(57) **CLAIM**

The ornamental design for “information containing attachment for the rear surface of a wristwatch”, set forth in the following as shown and described.

DESCRIPTION

FIG. 1 is a front elevational view of an information containing attachment for the rear surface of a wristwatch showing my new design, with the broken line showing for illustrative purposes only and forming no part of the claimed design.

FIG. 2 is a plan view of the invention;

FIG. 3 is a rear view of the invention;

FIG. 4 is a side view of the invention;

FIG. 5 is a side view of the information material of the invention; and,

FIG. 6 is a front view of the information material of FIG. 5.
